UNITED STATES PATENT OFFICE.

RICHARD E. SMITH, OF LIMA, OHIO.

WASHING-MACHINE.

1,269,513.

Specification of Letters Patent. Patented June 11, 1918.

Application filed August 6, 1917. Serial No. 184,701.

To all whom it may concern:

Be it known that I, RICHARD E. SMITH, a citizen of the United States, residing at Lima, in the county of Allen and State of Ohio, have invented certain new and useful Improvements in Washing-Machines, of which the following is a specification.

This invention relates to a washing machine and particularly to a machine driven by power for washing a large number of clothes at one operation, and has for its object to provide in such a machine a washing and a rinsing tub in which may be placed a perforated basket for holding the clothes to be cleaned, said basket through suitable gearing being given a rotary and also a vertically longitudinal movement.

Another object of the invention is to provide a washing machine of the class set forth with means for holding the basket at different points of elevation in the washing tub and in the rinsing tub and also with means for changing the speed of the basket, both rotary and reciprocating, upon changing said basket from one tub to the other.

A further object of the invention is to provide a washing machine which, while thoroughly efficient for the service desired, shall contain relatively few parts and which may be operated by persons unskilled in the use of machinery.

With the above as the principal objects in view, the invention consists in the novel construction, combination and arrangement of parts hereinafter described, pointed out in the appended claims and illustrated in the accompanying drawings, in which:

Figure 1 is a top plan view of the complete machine with the parts shown in position for washing the clothes,

Fig. 2 is a similar view showing the manner of changing the washing device from one tub to another, a portion of the machine being shown in section,

Fig. 3 is a vertical sectional view on the line 3—3 of Fig. 1,

Fig. 4 is a transverse sectional view on the line 4—4 of Fig. 3,

Fig. 5 is a detail view partly in section of the means for vertically reciprocating and rotating the clothes holding basket,

Fig. 6 is a detailed sectional view on the line 6—6 of Fig. 5,

Fig. 7 is a sectional view on the line 7—7 of Fig. 6,

Fig. 8 is a plan view showing the top of

the basket for holding the clothes to be washed, and

Fig. 9 is a detailed sectional view on the line 9—9 of Fig. 8.

In the drawings, 10 indicates a flat bench or table mounted upon legs 11 at the ends thereof and supporting upon its upper side a washing tub 12 and a rinsing tub 13. These tubs are preferably made of metal such as galvanized iron and each provided with a copper bottom 14. A cover 15 which may be of wood is adapted to fit over the tub that at the time, is in use. Mounted below the washing tub 12 is a lamp or other form of heating device 16, which, when the same consists of a lamp, is provided with oil from a reservoir 17 through a pipe 18.

Near one edge of the bench or table 10 and midway between the tubs 12 and 13 is a vertical shaft 19, rotatably and also longitudinally slidably in a bearing 20 secured to the bench or table and an upper bearing 21 supported by two downwardly extending braces 22, secured to the side of the bench or table 10. A third brace or bracket 23 passes between the tubs to the top of the bench or table and is secured thereto. By this means, the upper bearing is held rigidly in alignment with the lower bearing 20.

Below the top of the bench or table 10 the vertical shaft 19 has mounted thereon a beveled gear wheel 24 connected thereto by a sliding key so that the shaft may move longitudinally of said gear but be rotated thereby. Below the beveled gear 24 is a bearing 25 through which the shaft 19 passes and which rotates to a limited extent on said shaft. A boss 26 on one side of the bearing 25 receives one end of a horizontal shaft 27 carrying a beveled gear wheel 28 in mesh with the beveled gear wheel 24. The shaft 27 extends to near one end of the bench or table 10 and is provided on its outer end with a friction wheel 29, the end of the shaft just within said friction wheel passing through and is supported by a depending lever 30, pivoted at its upper end in a bracket 31 on the under side of the table and connected at its lower end through link 32, that extends across and below the table, to an upright hand lever 33, which passes upwardly through the bench and is pivoted at the upper side thereof, said lever terminating in a hand grip 34. A locking device 35 on said lever co-operates with

a notched segment 36 on the bench to hold the lever in any adjusted position.

Depending from the under side of the bench top 10 is a bracket bearing 37 in which 5 rotates a short shaft 38, its outer end being provided with a drive pulley 39 adapted to be rotated from any source of power, while its inner end has keyed thereon a flanged friction pulley 40 having a friction hub 41 10 within the flanged portion thereof. The friction wheel 29 extends within the flanged pulley 40 and by means of the hand lever 33, may be brought into engagement with said hub or with the inner surface of the flange 15, thereby changing the speed and also the 15 direction of rotation of the friction wheel, its shaft 27 and through the gearing the vertical shaft 19.

Pivoted to swing horizontally about the 20 upper end of the vertical shaft 19 is a horizontal rod 43 having a bearing 44 on one end for mounting the same on the shaft 19, said rod extending across the cover 15 at one side and to which hinges 45, secured to the 25 top 15 are pivoted. Above the bearing 44 is a beveled pinion 46 secured to the upper end of shaft 19, said pinion meshing with a like pinion 47 on one end of a horizontal shaft 48 journaled in an upright bracket 30 member 49 bolted on the cover 15 and extending to the center thereof. The opposite end of the shaft 48 carries a beveled gear 50 engaging a beveled pinion 51 mounted on a vertical shaft 52 passing through the inner 35 end of the bracket member 49 and centrally through the cover 15, the lower end of said shaft supporting a clothes carrying basket 53. The shaft 52 is adapted to slide vertically through the beveled pinion 51, being 40 rotated by said pinion through a key movable in a key-seat 52^a extending longitudinally of the shaft 52. The basket 53 is of cylindrical shape, having sides which are preferably formed of perforated sheet metal 45 and having a bottom of reticulated or woven mesh material. The basket is closed by a two-part top 54 hinged together at 55 in the central line so that either side may be raised when desired.

50 Carried by the shaft 52 is a block 57 slideable upon said shaft and secured thereto by a key 58 having a flat side 59 which, when turned toward the shaft 52, permits said block to slide longitudinally on the shaft, as 55 in Fig. 7, but when turned half around, said key engages one of two grooves 60 and 61 formed in said shaft and locks said block against horizontal movement. In one side of said block is a horizontal groove 64 adapted 60 to receive a roller 65, on one end of a crank pin 66 that projects from the adjacent face of the beveled gear 50 and serves to impart a vertical reciprocating movement to the shaft 52 and basket 53 as the beveled 65 gear rotates. At the same time the bevel

gear 50 actuates the beveled pinion 51 and rotates said shaft.

In the operation of the above described washing machine, the clothes to be washed are placed in the basket 53 and the latter in 70 the washing tub 12 and lowered to the bottom of said tub by turning the key 58 so that the flat portion 59 will permit the shaft 52 to slide freely past the key, if the shaft should be in elevated position. When the 75 groove 60 in said shaft reaches the key 58, the latter is turned to cause engagement of the key with the groove and prevent the shaft and basket 53 descending lower. A suitable amount of water is run into the tub 80 and the heater 16 lighted to keep the water at a high temperature. The hand lever 33 is then moved to cause the friction disk 29 to engage the hub 41 on the shaft 38 whereby the shaft 27 is rotated at a relatively slow 85 speed, which shaft through the beveled gears 28 and 24, vertical shaft 19 and the beveled pinion 46 rotate the beveled gear wheel 50 which through its engagement with the beveled pinion 51 rotates the shaft 52 and basket 90 53 and also through the crank pin 66 on the beveled wheel 50 imparts a vertical reciprocating movement to said shaft and the clothes basket. This movement of the basket 53 causes the water in the tub 12 to circulate 95 thoroughly through the clothes and by means of soap and other chemical substances in the water, thoroughly clean them.

After the clothes have been washed, the 100 operation is halted by moving the hand lever 33 a sufficient distance to bring the friction disk 29 into position between the hub 41 and the flange of the friction pulley 40. The vertical shaft 52 can then be raised after turning the key 58 as previously described, until the groove 61 is in position to be engaged by the key. In this position the basket 53 will be near the top of the tub and in wringing position. The next step is to raise the vertical shaft 19 by 105 110 sliding it in its bearings and lifting all that part of the mechanism supported by said shaft to the position indicated in dotted lines in Fig. 3. From this position, the elevated portions are swung around as indicated in Fig. 2 until they are over the rinsing tub 13 when they are lowered so that the basket 53 will enter the tub and the top 15 be supported on the upper edge of the tub. The friction disk 29 is now 115 120 moved into engagement with the inner surface of the flange 42 of the pulley 40 so that the speed of the rotating parts will be increased and though rotating in a direction opposite that when washing, such 125 movement is immaterial to the proper operation of the machine as the basket 53 may rotate in either direction with the same result. The clothes being rinsed thoroughly, they are removed by raising the top 54 of 130

the basket. After the washing is completed, the water is removed from the tubs through faucets 70 and 71 connected to the bottoms of said tubs.

5 What is claimed is:

1. In a washing machine the combination with adjacently supported washing and rinsing tubs, a vertical shaft between said tubs, adapted to rotate and to be moved longitudinally, a bracket journaled on said shaft, a clothes basket supported by said bracket in position to be swung over and inserted in either of said tubs, means rotatable by said shaft for imparting to said basket a simultaneous rotary and rectilinear movement, means for driving said shaft, and shifting means operating on said driving means for causing it to rotate at different speeds.
2. In a washing machine the combination with adjacently supported washing and rinsing tubs, a vertical shaft between said tubs adapted to rotate and to be moved longitudinally, a bracket journaled on said shaft, a clothes receptacle, an upright shaft projecting upwardly from said clothes receptacle and rotatable in said bracket, gears operated by said first named shaft for imparting a rotary and rectilinear movement through the upright shaft to the clothes receptacle, and driving means for said vertical shaft for optionally imparting different speeds thereto.
3. A clothes washing machine comprising a washing tub and a rinsing tub ad-

jacently supported, a vertical shaft between said tubs, a swinging bracket on said shaft, a clothes receptacle, an upright shaft fastened to said receptacle and journaled in said bracket to move longitudinally and 40 adapted to swing freely with said bracket over either of said tubs for insertion thereto, driving mechanism between the vertical shaft and said receptacle for imparting a simultaneous rotary and rectilinear 45 movement thereto, and driving means for the vertical shaft capable of being rotated at different speeds.

4. A washing machine comprising a stand or bench, a washing tub and a rinsing tub 50 adjacently supported thereon, a vertical shaft journaled on said bench between the two tubs adapted to be rotated at different speeds, a bracket pivotally mounted on the top of the vertical shaft to swing horizontally, an upright shaft rotatably and longitudinally movable in the outer end of said bracket and adapted to enter either tub, a clothes receptacle on the lower end of the upright shaft, and driving means between said latter shaft and said vertical shaft for imparting simultaneous movement to the receptacle.

In testimony whereof I affix my signature in presence of two witnesses.
